UNITED STATES PATENT OFFICE.

LUCIUS ALVORD, OF HOMER, NEW YORK.

STANCHION.

SPECIFICATION forming part of Letters Patent No. 434,012, dated August 12, 1890.

Application filed July 19, 1889. Serial No. 318,009. (No model.)

To all whom it may concern:

Be it known that I, LUCIUS ALVORD, of Homer, county of Cortland, in the State of New York, a citizen of the United States, have invented certain new and useful Improvements in Cattle-Stanchions, of which the following is a specification, reference being had to the accompanying drawings, in which—

Figure 1 is a side elevation of a part of a row of stanchions. Fig. 2 is a like view of a part of a row, showing another connection. Fig. 3 is a like view showing a strip-connection. Fig. 4 is a detached isometrical view of the lock-block. Fig. 5 is a like view of the saddle.

My invention relates to the construction of stanchions for cattle.

My object is to improve their construction by connecting stanchion-bars together, so that they may be all operated at once to open or close them, or may be operated singly.

My invention consists in the several novel features of construction and operation hereinafter described, and specifically set forth in the claim annexed hereto.

It is constructed as follows:

A A are the stationary vertical bars of the stanchion secured at the bottom to a base of ordinary construction and at the top to top bars or between the ordinary top bars.

B B are the movable vertical bars pivotally connected to the base at the proper distance from the stationary bars A, and at the top fitting between the bars constituting the top frame-work and adapted to slide freely between them. Adjacent to the upper end of each bar B, I insert a transverse pin 1.

C is a saddle fitting over the upper ends of the stanchion and resting upon the pin 1 on each side. This saddle consists of a band of metal of proper size to fit loosely upon the stanchion, and is provided upon its ends with ears 2, and I usually provide it also with a concavity α in each edge, which concavity fits upon the pin, and the saddle rocks upon the pin. The saddles are connected to each other by cords or wires 3, secured to the ears.

4 is a cord or wire passed around a pulley 5 at the end of the row of stanchions, and thence

over pulleys 6 and 7 to the opposite end of 50 the row or to any other place desired. It will be readily observed that when the stanchions are closed, as in Fig. 1, by pulling upon the cord 4 the stanchions will all open simultaneously, falling over against the inclined 55 faces of the uprights A, provided they are first unlocked.

D is the lock, consisting of a block of wood mortised to fit loosely over the stanchion at the end of a row and pivoted upon that stanchion, and also provided with a mortise 8 of proper size to fit over the projecting top of the last stationary upright in the row. In Fig. 2 I show the wire continuous, bent at the proper points to form a ring or eye 9, which 65 ring or eye fits loosely over the pin 1 in the stanchions, thus dispensing with the saddle c. In Fig. 3 I show the stanchions connected by a strip of wood or iron pivotally connected to the top of each movable stanchion, and in 70 this construction when the bars are unlocked by pulling upon the strip the stanchions are opened, and by pushing upon it they are closed, simultaneously, and as the pins 1 are removable by removing any pin that stanchion-bar can be operated independently of the rest, and the same can be done when the continuous wire is used, as in Fig. 2, by removing any pin, or in Fig. 1 by lifting any saddle off from its stanchion.

What I claim as my invention, and desire to secure by Letters Patent, is—

The combination, with the vertical bars and the swinging bars mounted in a base and a top piece, of the pins inserted transversely 85 through the swinging bars, the saddle fitting over the bars and separately detachable therefrom and resting upon the pins, means for connecting the saddles between the bars, means for operating the bars simultaneously to open 90 or close all at once, and a lock locking the end bar of a row to the end upright, as set forth.

In witness whereof I have hereunto set my hand this 12th day of July, 1889.

LUCIUS ALVORD.

In presence of—

I. S. POMEROY,

W. H. CRANE.
